A. J. ADAMS

MANUFACTURE OF SPOKES

Filed Feb. 17, 1921

Inventor:

Arthur J. Adams,
Bydeworth, La., Clinton Mills,
Atty.

UNITED STATES PATENT OFFICE.

ARTHUR J. ADAMS, OF BAY CITY, MICHIGAN, ASSIGNOR TO THE FULTON COMPANY, OF BAY CITY, MICHIGAN, A CORPORATION OF MICHIGAN.

MANUFACTURE OF SPOKES.

Application filed February 17, 1921. Serial No. 445,617.

To all whom it may concern:

Be it known that I, ARTHUR J. ADAMS, a citizen of the United States, residing at 615 Jackson Street, Bay City, in the county of 5 Bay and State of Michigan, have invented a new and useful Improvement in the Manufacture of Spokes, of which the following is a specification.

This invention relates particularly to the 10 manufacture of tubular metal spokes for the wheels of small vehicles, such as perambulators, go-carts, children's sulkies and the like. My main object is to provide a desirable and inexpensive method of manufacturing spokes which can be employed to provide a staunch and durable wheel at moderate cost.

It is well known that the wire wheels commonly employed for perambulators and the like are not staunch and durable, and it is also true that the wooden "artillery" wheels which are in use are not entirely satisfactory. The present invention provides for the construction of a metal wheel which can 25 be manufactured at moderate cost, which can be subjected to an enameling operation with facility, which is exceedingly strong and durable, and which presents a pleasing appearance.

30 The invention is illustrated in the accompanying drawing in which—

Fig. 1 represents a broken sectional view of a wheel provided with spokes formed in accordance with the invention; Fig. 2, a 35 broken elevational view of the wheel-hub; Fig. 3, a broken sectional view showing the relation of the spokes to the wheel-hub; Fig. 4, an inner view of one of the hub-plates employed; Fig. 5, a plan view of a 40 metal strip or blank employed in the formation of a spoke; Fig. 6 an elevational view of a tubular spoke formed from the blank shown in Fig. 5; Fig. 7, a broken perspective view showing the inner end of a spoke, and Fig. 8, a broken perspective view showing the outer end of a spoke.

In the drawing, the wheel is shown composed of tubular spokes A; a rim B; and a hub C.

50 The spokes A are formed from flat strips of metal of the form illustrated in Fig. 5.

The rim B may be made from a strip of sheet metal suitably rolled to make it of concavo-convex cross-section. The rim is 55 provided at its inner circumferential portion

with lugs or bosses 1 which are formed by punching the metal through.

The hub C comprises a hub-barrel 2, and a pair of hub-plates on each end of the barrel 2. Each hub-plate comprises an inner annular disk or plate 3 and an outer annular disk or plate 4. The plate 3 is provided with lugs 3^a adapted to be bent over the circumferential edge of the companion plate 4 to secure the hub-plates together in 60 the manner shown in Fig. 2. The hub-plates are provided with half cylindrical radial embossments which are complementary and afford sockets 5 for the inner ends of the spokes. The spokes have their inner 65 ends entered into the sockets and their outer ends engaging the bosses 1 of the rim; and the pairs of hub-plates are then forced towards each other, thus placing the spokes 70 under compression. The ends of the barrel 75 2 are spun outwardly to provide retaining flanges 2^a. The barrel 2, which may be formed from a sheet metal blank by rolling it into tubular form, is provided with outwardly struck bosses 6 which are adapted 80 to afford stops engaged by the inner members of the pairs of hub-plates.

The metal strip or blank shown in Fig. 5 is provided at the end which corresponds 85 with the inner end of the spoke with a central concavity 7 and with beveled and slightly recessed corners 8, the metal at the corners being cut away more deeply than at the recess 7. When the strip is formed into a tube, the recess 7 and the recesses 90 formed by the cut-away corners 8 provide diametrical opposite concavities which are adapted to fit against the convexity of the hub-barrel; and it will be noted that the concavity afforded by the complementary recess 8 is deeper, or lower, than is the concavity 7. This is to enable the walls of the concavities to engage the hub-barrel 95 properly while the spoke is in the inclined position shown in the assembly in Fig. 1. 100

The blank is further provided at the end corresponding with the inner end of the spoke with intermediate recesses or concavities 9 disposed between the central concavity 7 and the cut away corners of the blank. 105 The purpose of the recesses 9 is to cut away the metal sufficiently to enable the inner ends of adjacent spokes to be closely nested in the manner shown in Fig. 3.

At the end of the blank which corresponds 110

2
with the outer end of the spoke, the strip is provided with concavities or recesses 10 which flank the longitudinal axis of the strip. This provides high points 11 at the 5 corners and a high point 12 at the center, the point 12 being preferably slightly lower, however, than the points 11. When the strip is formed into a tube the lateral edges of the strip are made to meet along the line 13, as 10 shown in Fig. 6. It will be noted from Fig. 6 that the concavities 7 and 8 are diametrically opposite each other and in the plane which contains the meeting edges 13 of the strip; and it will be noted that the concavities 15 10 at the other end of the spoke are diametrically opposite each other, but on an axis at right angles to the axis of the concavities 7 and 8. Thus, the concavities 7 and 8 are adapted to engage the hub-barrel, 20 while the concavities 10 are adapted to engage the convex surface of the rim. In assembling the wheel, the seams 13 of the spokes are turned inwardly, so that at their outer sides the spokes present the appearance 25 of seamless tubes. After the wheel has been assembled and before the tire is applied, the wheel is dipped in enamel and then baked, so that the joints become covered with enamel and are practically unnoticeable.

The improvement enables an exceedingly staunch, durable and attractive wheel to be manufactured at very moderate cost.

What I regard as new, and desire to secure by Letters Patent, is:

1. The method of making a tubular spoke which comprises providing one end of a flat strip of metal with a central concavity and chamfered corners, and then forming the

strip into a tube, whereby said end of said 40 spoke is provided with diametrically opposite concavities.

2. The method of making a tubular spoke which comprises providing one end of a strip of metal with a central concavity and 45 chamfered corners cut lower than the central depression, and then forming the strip into a tube, whereby said end of said spoke is provided with diametrical opposite concavities, the concavity formed by the chamfered corners being deeper than the other concavity.

3. The method of making a tubular spoke which comprises providing one end of a metal strip with a central concavity and 55 chamfered corners and providing the other end with two concavities flanking the axis of the strip, and forming the strip into a tube, whereby the tube is provided at the first mentioned end with diametrically opposite recesses adapted to fit a hub-barrel and is provided in a plane at right angles thereto, at the other end, with diametrically opposite recesses adapted to fit a rim.

4. The method of making a tubular spoke which comprises providing one end of a metal strip with a central recess and with intermediate recesses flanking the central recess and with chamfered corners, and 60 forming the strip into a tube, whereby said end of said spoke is provided with diametrical opposite concavities adapted to fit a hub-barrel and at right angles thereto with recesses enabling the inner end of the spoke to be closely nested with relation to adjacent 70 75 spokes.

ARTHUR J. ADAMS
